15 two hands in the act of throwing the same. At the junction of the handle and bowl of the spoon is a representation of the "small" and flukes of a whale, with the flukes toward the bowl of the spoon.

is a representation of a portion of the sea, a 20 sperm whale in the middle distance, a whale-boat under sail with the figure of a man in the bow in the act of striking the whale with a harpoon, a ship in the far distance, and flying birds. 25

What I claim is—

A spoon provided with the design herein shown and described, the same comprising a harpoon represented on the handle of said spoon, the small and flukes of a whale represented at the junction of the handle and bowl, and the bowl containing a representation of a portion of the sea, a whale, a whale-boat, a ship, and birds. 30
